[57] ABSTRACT

A comparatively small electronic inventory control device for indicating the current stocks of goods, individually or in succession. The item numbers of the goods are selectively entered by push-button switches. New information for updating the stocks is entered by the same switches. Numerals for item number and the information are differentiated by separate manual switch means. A rotary memory means having addresses corresponding to the item numbers of the goods is used for storing and updating the stock information of the goods.

INVENTORY CONTROL DEVICE

This invention relates to an inventory control device, and more particularly to a comparatively small and inexpensive inventory control device which is suitable for controlling the stock of goods in retail and wholesale stores and manufacturing factories.

At the present, the stock of goods is usually controlled based on the so-called slip system by using a slip for each movement of goods into or out of the stock, and by transferring the description in the slip to a ledger by copying it. With such slip system, the stock at a desired moment is determined by the record in the ledger or by personally checking the actual stock at the moment. The record in the ledger is susceptible to clerical errors, such as miscalculation and overlooking, while the personal checking is not only tedious and time-consuming but also susceptible to personal errors. To avoid such difficulty of the slip system, use of electronic computers is proposed for inventory control, but electronic computers currently available in market require skilled operators and a considerably large fund for installation. Accordingly, computerized inventory control has been adopted only by large organization which can justify the use of costly computers and skilled operators for overall information processing, of which the inventory control assumes a small part. In the case of comparatively small organization, it is difficult to efficiently use the electronic computer of general type, even if its cost is not formidable. For instance, inquiries on small quantity of goods must be quickly processed and answered, but the preparation of a computer program for determining the stock of the inquired goods followed by card or tape punching and the computer operation will cause a too long delay in answering such inquiries. Only large organizations can make it a routine process to handle stocks of a large number of different goods at reasonable cost. Thus, despite the well-recognized need for the computerized inventory control, it has not been met heretofore, as far as comparatively small organizations are concerned.

Therefore, an object of the present invention is to meet the aforesaid need, by providing a comparatively small and inexpensive inventory control device which can easily be operated at a high efficiency.

According to the present invention there is provided an inventory control device, which comprises a keyboard, coder, a function setter, a function register, a code register counter, an input-output register, an address counter, a coincidence circuit, a counter decoder, an order circuit, and an adder-subtractor, whereby the stock of each goods under control can selectively and/or successively be read and can be updated in response to the removal and addition of the corresponding goods.

Other objects and a fuller understanding of the present invention may be had by referring to the following description, taken in conjunction with the accompanying drawings, in which:

FIG. 1 consisting of FIGS. 1A and 1B is a block diagram of an inventory control device, according to the present invention;

FIG. 2 is a schematic circuit diagram of a different part in the device of FIG. 1; namely, a keyboard and a coder;

FIG. 3 is a schematic circuit diagram of a different part in the device of FIG. 1; namely, a function setter;

FIG. 4 is a schematic circuit diagram of a different part in the device of FIG. 1; namely, a function register;

FIG. 5 consisting of FIGS. 5A and 5B is a schematic circuit diagram of a different part in the device of FIG. 1; namely, an I/O register;

FIG. 6 consisting of FIGS. 6A and 6B is a schematic circuit diagram of a different part in the device of FIG. 1; namely, a code register counter;

FIG. 7 is a schematic circuit diagram of a different part in the device of FIG. 1; namely, a counter decoder;

FIG. 8 is a schematic circuit diagram of a different part in the device of FIG. 1; namely, an indicator scanner;

FIG. 9 consisting of FIGS. 9A and 9B is a schematic circuit diagram of a different part in the device of FIG. 1; namely, an indicator with its driver;

FIG. 10 is a schematic circuit diagram of a different part in the device of FIG. 1; namely, a track-selector;

FIG. 11 is a schematic circuit diagram of a different part in the device of FIG. 1; namely, a reader-writer;

FIG. 12 is a schematic circuit diagram of a different part in the device of FIG. 1; namely, a bit counter;

FIG. 13 is a schematic circuit diagram of a different part in the device of FIG. 1; namely, a place counter;

FIG. 14 is a schematic circuit diagram of a different part in the device of FIG. 1; namely, an address counter;

FIG. 15 is a schematic circuit diagram of a different part in the device of FIG. 1; namely, a coincidence circuit;

FIG. 16 consisting of FIGS. 16A and 16B is a schematic circuit diagram of a different part in the device of FIG. 1; namely, a gate circuit;

FIG. 17 consisting of FIGS. 17A and 17B is a schematic circuit diagram of a different part in the device of FIG. 1; namely, an adder-subtractor; and

FIG. 18 consisting of FIGS. 18A and 18B is a schematic circuit diagram of a different part in the device of FIG. 1; namely, an order circuit.

Like parts are designated by like numerals and symbols throughout the drawings.

In the preferred embodiment, as illustrated in the accompanying drawings, various integrated circuit (IC) elements are used as logical elements of the inventory control device, and such logical elements are designated by conventionally used symbols of IC. A circle (O) indicated at the input or output of the IC element means that negation of the input or output is valid, respectively. Depending on the location of the circle mark, the IC elements are referred to as follows; namely, OR-type NAND elements, AND-type NAND elements, input-negation-type NOT elements, and output-negation-type NOT elements. Although IC elements are used for the logical elements in the preferred embodiment, it is apparent that transistor-type logical elements can also be used in the inventory control device of the present invention.

Referring to FIG. 1, a register 1 acts to enter both the item numbers representing different goods and the stock information, which constitute the input to the inventory control device. As can be seen from FIG. 2, the keyboard 1 comprises push-button switches 1a0 to 1a9, representing the corresponding decimal numerals zero to nine, respectively. A coder 2 receives decimal signals from the keyboard 1, and converts them into parallel binary signals, which binary signals are used as control output signals and contents output signals. To this

end, the coder 2 comprises OR-type NAND elements 3a1 to 3a4, another OR-type NAND element 3b, AND elements 4a1 to 4a4, a NOR element 5, an input-negation-type NOT element 6, flip-flop elements (to be referred to as FF elements, hereinafter) 7 and 8, and an AND-type NAND element 9, as shown in FIG. 2. In the figure, SP represents synchronizing pulse (synchro-pulse) delivered from a reader-writer 54, while timing signals MSB, MMSB, MLSB, and LSB are applied to the coder 2 from a bit counter 65 to be described hereinafter. The output signal OS1 from the AND-type NAND element 9 is used as a control signal, and the output signal KIN from the NOR element 5 is used as a contents signal.

A function setter 10 acts to specify the function of the numerals provided by the keyboard 1. As shown in FIG. 3, the function setter 10 includes a number of switches, consisting of an operation-starting key switch 11a1, an item number reading push-button switch 11a2, an information-adding push-button switch 11a3, an information-subtracting push-button switch 11a4, an erasing push-button switch 11a5, and a successive reading push-button switch 11a6. In addition, the function setter 10 comprises an input-negation type NOT element 12, a resistor 13, an OR-type NAND element 14, an output-negation-type NOT element 15, FF elements 16 and 17, and an AND-type NAND element 18. Synchronizing pulse SP is applied to the FF elements 16 and 17 of the function setter 10, while the contents output signals AS, PL, MI, CL, and +1 from the function setter 10 are applied to a function register 19. A control output signal OS2 from the AND-type NAND element 18 is delivered to the gate circuit 75. When the key switch 11a1 is not closed, the results of operation caused by the depression of the push-button switches 11a3 and 11a4 are inhibited from being written.

The function register 19 acts to convert the instantaneous output signal OS2 from the function setter 10 (lasting only when the push-button switches are being depressed) into a continuous signal, which is delivered to the next succeeding stage element in response to specific timing signals. Referring to FIG. 4, the function register 19 includes a converter 20 for producing the aforesaid continuous signal, which converter comprises input-negation-type NOT elements 20a1 to 20a6 and AND-type NAND elements 20b1 to 20b4. The function register 19 further includes an input-negation-type NOT element 21, AND-type NAND elements 22a1 and 22a2, OR-type NAND elements 23a1 to 23a4, output-negation-type NOT elements 24a1 to 24a4, and FF elements 25a1 to 25a4.

The input signals to the function register 19 include contents output signals AS, +1, PL, MI, AND and the control output signal OS2 from the function setter 10, control output signal OS1 from the coder 2, output signals DDCO and DCL from a coincidence circuit 70, output signals END and *** from an order circuit 88, and a clock pulse CP read out of a magnetic drum 53. The function register 19 generates output signals which include signals 2AS and (+1) for a code register counter; signals ASF, PLF, PLF, MIF, and MIF for the order circuit 88; and signals NKFL, PLF, and MIF for the gate circuit 75. As can be seen from FIG. 4, the two output signals PLF and MIF are applied to the order circuit 88 and the gate circuit 75.

An input-output (I/O) register 26 (stock information register) acts to temporarily store binary numeral sig-

nals delivered from the coder 2 or the gate circuit 75. Referring to FIG. 5, for fulfilling this end, the I/O register 26 comprises output-negation-type NOT elements 27a1 to 27a5, AND-type NAND elements 28a1 to 28a4, an OR-type NAND element 28b, and FF elements 29a1 to 29a16, which are connected as shown in the figure.

Of the input signals to the I/O register 26, RIN, NKSRC, RST, and NSRK signals are output from the 10 gate circuit 75, while KIN signal is the contents output from the coder 2. Of the output signals from the I/O register 26, signals 511, 511, 512, 512, 514, 514, 518, 518, 521, 521, 522, 522, 524, 524, 528, 528, 531, 531, 532, 532, 534, 534, 538, and 538 are applied to both 15 the code register counter 30 and an indicator scanner 38, while signals 541, 541, 542, 544, 544, 548, and 548 are applied to the indicator scanner 38. The output signal 511 is also applied to an adder-subtractor 78. The I/O register 27 also generates a 1-detection signal and a 0-detection signal, which are both applied to the code register counter 30.

The function of the code register counter 30 is to store the contents of item number delivered from the I/O register 26 and the transfer such contents to the indicator scanner 38 and the coincidence circuit 70. In FIG. 6, the code register counter 30 comprises AND-type NAND elements 31a1 to 31a29, OR-type NAND elements 32a1 to 32a12, output-negation-type NOT element 33a1 to 33a12, and counters 34a1 to 34a13. 25 The input signals to the code register counter 30 include the +1 signal and 2AS signal from the function register 19; the 1-detection signal and 0-detection signal from the I/O register 26; and the signals 511, 511, 512, 512, 514, 514, 518, 518, 521, 521, 522, 522, 524, 524, 528, 528, 531, 531, 532, 532, 534, 534, 538, and 538 from the I/O register 26. The code register counter 30 generates output signals applied to the coincidence circuit 70, which output signals are 411, 411, 412, 412, 414, 414, 418, 418, 421, 421, 422, 422, 424, 424, 428, 428, 431, 431, 432, 432, 434, 434, 438, 438, 441, and 441. Of the last mentioned output signals from the code register counter 30, affirmative output signals are applied to the indicator scanner 38.

Timing signals for actuating the indicator scanner 38 45 together with an indicator driver 43 are generated by a counter decoder 35, based on the output signals (parallel signals) from an address counter 68. Referring to FIG. 7, the counter decoder 35 comprises AND-type NAND elements 36a1 to 36a8 and input-negation-type NOT elements 37a1 to 37a8. The input signals to the counter decoder 35 are output signals 321, 321, 322, 322, 324, 324, 328, and 328 from the address counter 68, while the output signals DT1 to DT8 are applied to the indicator scanner 38 and the indicator driver 43 as the input signals thereof.

The indicator scanner 38 is to generate scanning signals for actuating the indicator driver 43, based on the binary numeral output signals from either the I/O register 26 or the code register counter 30, in response to the timing signals delivered from the counter decoder 35. As can be seen from FIG. 8, to fulfill the aforesaid function, the indicator scanner 38 comprises AND-type NAND elements 39a1 to 39a4, 40a1 to 40a4, 41a1 to 41a4, 42a1 to 42a4, 39b1 to 39b4, 40b1 to 40b4, 41b1 to 41b4, and 42b1 to 41b4. For those NAND elements of the indicator scanner 38 which are shown above the dash-dot line of FIG. 8, contents sig-

nals 511, 512, 514, 518, 521, 522, 524, 528, 531, 532, 534, 538, 541, 542, 544, and 548 are applied from the I/O register 26, along with timing output signals DT1 to DT4 from the counter decoder 35. For the remaining NAND elements of the indicator scanner 38 below the dash-dot line, contents signals 411, 412, 414, 418, 421, 422, 424, 428, 431, 432, 434, 438, 441, 441, and OV are applied from the code register counter 30, along with timing output signals DT5 to DT8 from the counter decoder 35. The indicator scanner 38 applies its output signals 1B, 2B, 4B and 8B to the indicator driver 43.

The indicator driver 43 functions to transfer the contents output signals from the indicator scanner 38 to an indicator 46, based on the timing output signals from the counter decoder 35, so as to correspondingly actuate the indicator 46. Referring to FIG. 9, the indicator driver 43 consists of output-negation-type NOT elements 44a1 to 44a4, resistors 45a1 to 45a10, diodes d1 to d40, and transistors Tr1 to Tr10.

The indicator 46, as shown in FIG. 9, includes indicator tube elements H1 to H8, representing eight digits for numerical indication. For simplicity's sake, the details of the indicator tube element is illustrated only for the element H1, but the other elements H2 to H8 have similar construction as H1. Each indicator element H1 to H8 comprises resistors 47a1 to 47a7, transistors 47b1 and 47b2, a capacitor 47c, and a lamp 47d. Output signals DT1 to DT8 from the counter decoder 35 are applied to the indicator tube elements H1 to H8 as the timing signal, respectively. In the illustrated embodiment, four indicator tube elements H1 to H4 are used for stock information indication, while the remaining elements H5 to H8 are for item number indication. Accordingly, the first four elements H1 to H4 may be referred to as the stock information indicating section, while the second four elements H5 to H8 as the item number indicating section.

A track-selector 48 is provided in order to make selection of the tracks of the magnetic drum 53, in response to the output from the code register counter 30. In FIG. 10, the track-selector 48 is made by suitably connecting diodes d1' to d32' and amplifiers 49a1 to 49a8. As detailed for the amplifier 49a1, each amplifier of the track-selector 48 comprises transistors Tr1' and Tr2' interconnected by resistors r1 to r4. The input signals to the track-selector 48 are output signals 431, 431, 432, 432, 434, 434, 438, and 438 of the code register counter 30.

The track-selector 48 is connected to a tracking head 50 coacting with the magnetic drum 53. As shown in FIG. 10, the tracking head 50 comprises detecting coils 51a1 to 51a8, diodes 51b1 to 51b8, diodes 51c1 to 51c8, and resistors 52a1 and 52a2. Input signals DRO and DRO are applied to the tracking head 50.

Referring to FIG. 11, the reader-writer 54 for writing and reading signals into and out of the magnetic drum 53 comprises a synchro-pulse reading head 55a1 connected to an amplifier 55b1; a clock-pulse reading head 56a1 connected to an amplifier 56b1; a read-write timing element 57 having resistors r1' to r4', capacitors C1 to C3, and output-negation-type NOT elements N1 and N2; a memory element 58 having a pair of OR-type NAND elements 58a1 and 58a2; AND-type NAND elements 59a1 to 59a3; input-negation-type NOT elements 60a1 and 60a2; an amplifier 60 having transistors T1 to T4 and resistors 61a1 to 61a6; another am-

plifier 62; resistors 63a1 and 63a2; and capacitors 64a1 and 64a2.

When writing input signals WRIN and WRIN are applied to the reader-writer 54 from the gate circuit 75, the output signals DRO and DRO from the reader-writer 54 are delivered to the magnetic tracking head 50, so as to write certain information into specified address on specified track of the magnetic drum 53. On the other hand, when reading input signal is applied to the reader-writer 54 while removing the aforesaid writing input signals therefrom, input signals DRO and DRO to the reader-writer are generated by reading the information stored at the specified address, so as to deliver its output signal DROUT toward the adder-subtractor 78. The heads 55a1 and 56a1 act to read out synchro-pulses SP and clock-pulses CP from the timing track of the magnetic drum 53, which pulses SP and CP are stored prior to the reading.

The A counter 65 acts to count the clock-pulses CP, by using the timing of the synchro-pulses SP. In FIG. 12, the A counter 65 for counting four bits is comprised of counter elements C11, C12, C13, and C14, which are connected so as to constitute a shift register. Each counter element consists of an FF element. The A counter 65 also includes an OR-type NAND element 66 for generating an erasing signal 1100 (a "0" signal in excess-three code). The output bits LSB, MLSB, MMSB, and MSB from the A counter 65 are applied to the coder 2. The output bit MSB is further delivered to the coincidence circuit 70 and the order circuit 88, and also acts as a carry signal to be applied to a B counter 67.

The B counter 67 acts to count the carry signal MSB from the A counter 65, based on the timing of the synchro-pulse SP. As shown in FIG. 13, the B counter 67 is a kind of shift register consisting of counter elements C21 to C24. The output bits LSD and MLSD from the B counter 67 are delivered to the adder-subtractor 78, and another output bit MSD of the B counter 67 is used as a carry signal for the address counter 68.

The address counter 68 is to detect an address in the magnetic drum 53 facing the tracking head 50, by counting the carry signal MSD from the B counter 67, based on the timing of the synchro-pulse SP. Referring to FIG. 14, the address counter 68 comprises counter elements C31 to C39, an output-negation-type NOT element 69a, an OR-type NAND element 69b, and an AND-type NAND element 69c. The address counter 68 generates output bits 311, 311, 312, 312, 314, 314, 318, 318, 321, 321, 322, 322, 324, 324, 328, 328, 341, and 341, which are all applied to the coincidence circuit 70.

The duty of the coincidence circuit 70 is to determine whether or not the output signals from the code register counter 30 and the address counter 68 are in agreement with each other at each digit, and if they are in agreement, the circuit 70 generates coincidence signals CO and CO, together with control signals DCO, DCO, DDCO, DDCO, AR100, and AR100. There is a certain timing relation between the coincidence signals and the control signals from the coincidence circuit 70. As illustrated in FIG. 15, to fulfill the aforesaid duty, the coincidence circuit 70 comprises AND-type NAND elements 71a1 to 71a18, output-negation-type NOT elements 72a1 and 72a2, FF elements 73a1 and 73a2, and an OR-type NAND element 74. The input signals to the coincidence circuit 70 include the output signal MSB

from the A counter 65 and the output signal DCL from the gate circuit 75. The coincidence circuit 70 generates output signals CO, DCO, AR100 to be applied to the gate circuit 75, output signals $\overline{CO}$, DCO, $\overline{DCO}$ to be applied to the adder-subtractor 78, output signals $\overline{CO}$, DCO, AR100, $\overline{AR100}$ to be applied to the order circuit 88, and an output signal DDCO to be applied to the function register 19. The output signal DCO is delayed from the coincidence signal CO by one digit, and the output signal $\overline{DCO}$ is a negation signal of the output signal DCO, and the output signal DDCO is further delayed from the DCO by one digit.

The gate circuit 75 acts to control the operation of the order circuit 88 and the adder-subtractor 78, in response to input signals thereto from the coincidence circuit 70 and other circuits. As shown in FIG. 16, the gate circuit 75 comprises OR-type NAND elements 76a1 to 76a10, AND-type NAND elements 76b1 to 76b18, input-negation-type NOT elements 77a1 to 77a11, resistors 78a1 and 78a2, and capacitors 79a1 and 79a2. The input signals to the gate circuit 75 include the output signals $\overline{PLF}$ and $\overline{MIF}$ from the function register 19, the writing order signal WR, its negation $\overline{WR}$, and reading order signal R from the order circuit 88, the output signals CO, DCO, and AR100 from the coincidence circuit 70, the output signals KEY-1, M1, PL, CL, and OS2 from the function setter 10, the erasing signal 1100 from the A counter 65, the output signal NKFI of the function register 19, the clock pulse CP, the output signal OS1 from the coder 2, the output signal DROUT from the reader-writer 54, the output signal 511 from the I/O register 26, the output signals INH and AR10 from the adder-subtractor 78, and the output signal MLSD from the B counter 67. The output signals from the gate circuit 75 are delivered to different elements; namely, the output signals INC and $\overline{INC}$ to the order circuit 88, the output signal AR to the adder-subtractor 78, the output signals NKSRC, RIN, NSRK, and RSN to the I/O register 26, the output signals WRIN and WRIN to the reader-writer 54, and the output signal DCL to the coincidence circuit 70, the adder-subtractor 78, and the order circuit 88.

The adder-subtractor 78 is to effect addition or subtraction of the information concerning the incoming or outgoing goods, relative to the information read out of a specified address of the magnetic drum 53. Referring to FIG. 17, for fulfilling this function, the adder-subtractor 78 comprises a complement converter element 79 having output-negation-type NOT elements 79a1 and 79a2, AND elements 79b1 and 79b2, and a NOR element 79c; AND elements 80a1 and 80a2; a NOR element 81; AND-type NAND elements 82a1 to 82a9; output-negation-type NOT elements 83a1 to 83a4; input-negation-type NOT elements 84a1 and 84a2; FF elements 85a1 and 85a2; a counter 85 having FF elements 85b1 to 85b4; a full-adder 86; and a correction element 87, based on excess-three code, having AND elements 87a1 to 87a4, NOR elements 87b1 and 87b2, a full-adder 87c, FF elements 87d1 and 87d2, output-negation-type NOT elements 87e1 and 87e2, and an AND-type NAND element 87f.

The input signals to the adder-subtractor 78 include the output signal 511 from the I/O register 26, the output signal MIF from the function register 19, the output signal DROUT from the reader-writer 54, the output signals CO, DCO, and the output signals $\overline{DCO}$ from the coincidence circuit 70, the output signals DCL and AR

from the gate circuit 75, the output signals LSD and MLSD from the B counter 67, and the output signals MSB and 1100 from the A counter 65. The adder-subtractor 78 generates output signals AR10 and 1NH, which are applied to the gate circuit 75.

The order circuit 88 acts to generate read signals R, $\overline{R}$ and write signals WR, $\overline{WR}$, in response to the signals delivered from the function register 19. As shown in FIG. 18, the order circuit 88 comprises AND-type 10 NAND elements 89a1 to 89a10, OR-type NAND elements 90a1 to 90a4, input-negation-type NOT elements 91a1 to 91a4, and FF elements 92a1 and 92a2. The input signals to the order circuit 88 include the output signals AR100, $\overline{AR100}$, DCO, and $\overline{DCO}$ from the coincidence circuit 70, the output signals ASG, PLF, $\overline{PLF}$, MIF, and $\overline{MIF}$ from the function register 19, the output signal MSB from the bit counter 65, the output signals MLSD and LSD from the B counter 67, the output signals INC, $\overline{INC}$, and DCL from the gate circuit 75, and the clock pulse CP. The order circuit 88 generates output signals R, $\overline{R}$, WR, and $\overline{WR}$ to be applied to the gate circuit 75, and other output signals *** and END to be applied to the function register 19. The signal END represents the end of operation.

For simplicity's sake, the flow of timing signals is not shown in FIG. 1.

The operation of the inventory control device of the aforesaid construction will now be described, by referring to the drawings. Let it be assumed that the inventory control device is used in a clothes shop, and the stock of men's semisleeve shirts of medium size is going to be checked. A four-digit code number "0217" is assumed to be assigned to the shirt. Of the four decimal digits in the item number, the third digit from the right represents the track number in the magnetic drum 53 wherein the information relating to this goods, i.e., shirts, is stored. The remaining three digits, namely, the fourth, the second, and the first digits from the right, represent the sector address in the track assigned by the third digit. For instance, the information relating to the goods represented by the item number 0217 is stored in the sector 17 of the second track in the magnetic drum 53.

In order to check the stock of the goods represented by the item number 0217, the inventory control device is energized and the item number 0217 is entered by the keyboard 1. More particularly, the push-button switches 1a2, 1a1, and 1a7 of the keyboard 1 are depressed in succession in the aforesaid order. The item number 0217 thus set by the push-button switches is transferred from the keyboard 1 to the coder 2, wherein the NAND elements 3a1 to 3a4 convert the decimal item number into binary signals. The binary signals are applied to the FF elements 7 and 8, which generate the control signal OS1 based on the binary signals at the moments determined by the synchro-pulse SP. The binary signals are also applied from the NAND elements 3a1 to 3a4 to the other NAND elements 4a1 to 4a4, for generating contents signals KIN in a series fashion in response to the timing signals MSB, MMSB, MLSB, and LSB from the bit counter 65.

The control signal OS1 is applied to the function register 19, which acknowledges the control signal OS1 by delivering a recognition signal NKFI to the gate circuit 75. Accordingly, the gate circuit 75 delivers the signal RST to the I/O register 26, so as to apply reset-gate signals to the FF elements 29a1, 29a2, 29a5, 29a6, 29a9,

29a10, 29a13, and 29a14, while applying set-gate signals to the other FF elements **29a3, 29a4, 29a7, 29a8, 29a11, 29a12, 29a15, and 29a16**. Thus, the I/O register **26** becomes ready for indication. Upon application of the timing signals **NSRK** from the gate circuit **75**, the contents signal **KIN** is shifted and transferred in succession to the indicator scanner **38**. The scanner **38** also receives timing signals **DT1** to **DT8** from the counter decoder **35**, in response to the signals **321** to **328** from the address counter **68**. In response to the contents signal **KIN** and the timing signals **DT1** to **DT8**, the indicator scanner **38** actuates the indicator driver **43**, so as to indicate the item number **0217** on the indicator **46**.

In this case, the indication at the indicator **46** varies in the sequence of **0000** → **0002** → **0021** → **0217** in response to the sequential depression of the push-button switches at the keyboard **1**. Such sequential indication is controlled by the successive shifting in the FF elements of the I/O register **26**.

The address counter **68** counts the clock pulse, which is read from the magnetic drum **53**, in cooperation with the A counter **65** and the B counter **67**. The count is accumulated during each rotation of the magnetic drum **53**, but it is reset at certain intervals of the rotation. Unless the function setter **10** is actuated, the contents of the code register counter **30** is kept empty, so that the order circuit **88** does not produce any order signal. Consequently, the circuit through both the gate circuit **75** and the reader-writer **54** is kept inactive, so that even if the coincidence circuit **70** generates a coincidence signal **CO** in each revolution of the magnetic drum **53**, no signal is read out of or written into the drum **53**.

Let it now be assumed that the item number reading push-button switch **11a2** of the function setter **10** is depressed. As a result, the function setter generates the control signal **OS2** and the contents signal **AS**, for delivering them to the function register **19**. The register **19** acts to deliver the signal **2AS** to the code register counter **30** and the other signal **ASF** to the order circuit **88**. In response to the signal **2AS**, the code register counter **30** opens its NAND elements **31a4** to **31a29**, for shifting the binary item number corresponding to the decimal, **0217**, from the I/O register **26** to the counter elements **34a1** to **34a13** of the counter **30**. With the item number thus shifted into the code register counter **30**, the coincidence circuit **70** starts the detection of the timing when the address counter **68** counts the address represented by the item number thus shifted, e.g., **0217**.

At this moment, the output signal **ASF** from the function register **19** is delivered to the order circuit **88**, for generating the read order signal **R** through the NAND elements **89a4** and **90a4** and the FF element **92a1**. (Since the signals **AR100**, **MSB**, and **MLSD** are not simultaneously present then, the NOT element **91a1** is held at "1" condition and the gate of the NAND element **89a1** is kept open.) In response to the read **R** signal from the order circuit **88** and the timing signal **DCO** from the coincidence circuit **70** and the clock pulse **CP**, the gate circuit **75** delivers its output timing signal **NKSRC** to the I/O register **26** for resetting the counter elements. In response to the clock pulse **CP** at this moment, the reader-writer **54** reads the information **DROUT** stored in the magnetic drum **53** at its track **2** address **17** (for instance, "0051"), which information **DROUT** is delivered to the gate circuit **75**. In response

to the read signal **R**, the gate circuit **75** generates the signal **RIN** carrying the information, which is delivered to the I/O register **26**. Thus, the information **0051** from the magnetic drum **53** is set in the I/O register **26**.

As a result, the indication of the information section of the indicator **46**, adjacent to the item number section currently showing **0217**, is changed from **0000** to **0051**.

After indicating the information, the order circuit **88** generates the **END** signal, which erases the read signal **R** emanating from the same order circuit. The **END** signal is delivered to the function register **19** for resetting the FF element **25a2**, so as to erase the **ASF** signal. Thus, the operation of reading out the stock of the goods represented by the item number **0217** is completed.

The successive read out operation, e.g., the read out of the stock of item number **0218** after reading the stock of the item number **0217**, will now be described.

For this purpose, the successive reading push-button switch **11a6** of the function setter **10** is depressed after completing the stock reading for the item number **0217**. The function setter **10** generates the control signal **OS2** and the contents signal **+1**, in response to the actuation of the switch **11a6**. Such control signal **OS2** and the contents signal **(+1)** are delivered to the function register **19**, which in turn generates the **ASF** signal and the **(+1)** signal. The last mentioned **(+1)** signal is delivered to the code register counter **30** for increasing the item number stored therein by one, for instance from **0217** to **0218**. Consequently, the item number indication at the indicator **46** is changed from **0217** to **0218**. The signal **ASF** from the function register **19** actuates the order circuit **88**, the gate circuit **75**, and the reader-writer **54** in a manner similar to the preceding item number, so that the stock information for the item number **0218**, for instance **0072**, is read out and transferred to the I/O register **26** for indication at the stock information indicating section of the indicator **46**. After completing the reading stock for the next item number, the order circuit **88** generates another **END** signal, for erasing the **R** and **ASF** signals.

The operation for modifying the stock information, in response to the incoming or outgoing goods, will now be described, together with the storing process of the stock thus modified. For this mode of operation, the key switch **11a1** of the function setter **10** is temporarily closed. Let it be assumed that **100** units of the goods represented by the item number **0217** is going to be added to the stock, in addition to the previously assumed **51** units. The item number **0217** is set in the inventory control device through its keyboard **1** in the aforesaid manner. The current stock, e.g., **0051**, for the item number **0217** is read out of the drum **53** by operating the push-button switch **11a2** of the function setter **10**, so as to store the item number **0217** in the code register counter **30**, while storing the stock information **0051** in the I/O register **26**. Thus, the indicator **46** shows **0217** and **0051** in its item number section and the stock information section, respectively.

The new stock information on the incoming goods, e.g., **0100**, is entered through the keyboard **1**. The new information is then converted into binary signals by the coder **2** and delivered to the I/O register **26**, so as to modify the previous stock information **0051** to its new value **0100**. At this moment, the adder push-button switch **11a3** of the function setter **10** is actuated, for

initiating the adding mode of operation. In response to the actuation of the adder push-button 11a3, the function setter 10 delivers the control signal OS2 and the contents signal PL to the function register 19, which in turn generates the signal PLF. In response to this signal PLF, the order circuit 88 generates the read signal R, so as to cause the gate circuit 75 to deliver the signal NKSRC and AR to the I/O register 26 and the adder-subtractor 78, respectively. The signal NKSRC regulates the I/O register 26 so as to transfer the signal 511 carrying the incoming goods information, i.e., 0100, to the adder-subtractor 78, starting from the lowest digit.

The full-adder 86 of the adder-subtractor 78 receives the signal 511 (carrying the incoming goods signal, e.g., 0100) at its terminal A, while receiving the read-out signal DROUT (carrying the current stock for the specified item number, e.g., stock information 0051 for the item number 0217) at another terminal B, so as to store the sum of the two signals (e.g., 0151) in the counter 85. The sum in the counter 85 is corrected, for the excess-three coding, by the correction circuit 87 and transferred to the gate circuit 75 as the signal AR10. In response to the AR10 signal, the gate circuit 75 delivers the RIN signal (now carrying the information 0151) to the I/O register 26 for setting it to the new value, e.g., 0151, thus determined by the RIN signal. Thus, the sum of the old stock information and the new information relating to the incoming goods is now stored in the I/O register 26.

Upon the setting of the I/O register 26, the order circuit 88 generates the END signal for erasing the R signal, but due to the presence of PLF signal, the order circuit 88 generates the write signal WR instead of the R signal. In response to the WR signal, the gate circuit 75 delivers NKSRC signal to the I/O register 26 for shifting its memory, e.g., 0151, into the write-in signal WRIN. The reader-writer 54 acts to write in the signal WRIN at the address 217 (track 2, sector 17) of the magnetic drum 53. After the writing, the order circuit 88 generates the END signal, for erasing the WR signal and generating the R signal at the circuit 88 itself, and for delivering the signal *** to the function register 19 for resetting the signal PLF at the register 19.

With the R signal thus generated, the reader-writer 54 acts to read out the information just stored (e.g., 0151) for the item number 0217, in response to the coincidence signal generated in the next succeeding revolution of the magnetic drum 53. The information thus read out is entered into the I/O register 26 and shown in the stock information indicating section of the indicator 46.

Finally, the order circuit 88 generates another END signal for erasing the R signal, so as to complete the modification of the stock information for the incoming goods.

The modification of the stock information for the outgoing goods can be effected in a similar manner. In this case, the item number of the related goods is entered into the inventory control device through the keyboard 1, and the current stock of the goods is read out by operating the push-button switch 11a2 of the function setter 10. After entering the number of the outgoing goods by the keyboard 1, the subtraction push-button switch 11a4 of the function setter 10 is actuated, for generating the subtraction signal MI together with the control signal OS2. Accordingly, the function register 19 generates its subtraction signal

MLF, so as to determine the difference between the current information and the information representing the outgoing goods, by means of the adder-subtractor 78, and the new stock information thus determined is stored and indicated. In the above process for the outgoing goods, the subtraction signal MLF causes the complement converter element 79 of the adder-subtractor 78 to carry out the subtraction of the outgoing goods signal in the I/O register 26 from the signal read out of the magnetic drum 53. Except such action of the complement converter element 79, the process for the outgoing goods is substantially identical with the process for the incoming goods, and hence, no further detail of the operation for the outgoing goods will be described here.

It is apparent that modification of the stock information can be effected in a similar manner for other goods having different item numbers. With the updating operation for each incoming or outgoing of the goods, the current stock of each goods can easily be read out from the magnetic drum 53 in the aforesaid fashion.

As described in the foregoing disclosure, according to the present invention, there is provided a comparatively small and inexpensive inventory control device, as shown in FIG. 1, which can easily be operated by actuating push-button switches in the keyboard 1 and the function setter 10 for modifying and recording the stock information for updating it and for read out. The inventory control device of the present invention is particularly suitable for retail and wholesale stores of medium and small scale, for efficient stock supervision.

Although the present invention has been described with a certain degree of particularity, it is understood that the present disclosure has been made only by way of example and that numerous changes in the details of construction and the combination and arrangement of parts may be resorted to without departing from the spirit and the scope of the invention as hereinafter claimed.

We claim:

1. An inventory control device which comprises in combination, a keyboard having 10 manually operable switches for selectively entering decimal numerals zero to nine in succession; a coder coupled for receiving and converting the decimal numeral from the keyboard into binary signals, said binary signals being control output signals and contents output signals, a function setter coupled to receive binary signals and having manually operable switches for selecting a mode of operation, said switches consisting of an operation-starting key switch, an item number reading push-button switch, an information-adding push-button switch, an information-subtracting push-button switch, an erasing push-button switch, and a successive reading push-button switch, a function register coupled to convert output signals from the function setter into a continuous signal, an indicator means, an indicator scanner connecting said function register and the indicator means, an I/O register coupled to the indicator scanner and the coder, a rotary memory means having addresses for storing stock data of goods in accordance with given item numbers representative of the goods, a magnetic head means coupled to the I/O register for reading from and writing in the stock data relative selected addresses of the memory means, said indicator means indicating the item number of a selected good along with

the stock information thereof received from said memory means.

2. An inventory control device which comprises in combination, a keyboard having ten decimal number push-button switches for entering a decimal number word, a coder coupled for receiving the decimal number from said keyboard with means for converting same to a corresponding binary number word, a memory unit having a non-volatile memory means with a reader-writer head, said non-volatile memory means having a number of memory locations, an address counter having means indicating a then read/writeable memory location, a read/write circuit including the read/write head, an I/O register coupled to said coder and said read/write circuit for temporarily storing information therefrom, a code register counter coupled to said I/O register for storing an item number from said I/O register representative of the address of a memory location, a coincidence circuit coupled to said code register counter and said address counter for detecting coincidence of the contents of said code register counter and said address counter to trigger said read/write circuit, an adder-subtractor coupled to said I/O register and said read/write circuit with means for effecting addition/subtraction of the contents of said I/O register with respect to information read out by said read/write circuit and means for returning the combined result to said read/write circuit through said I/O register, a function setter including at least three command generating switches for generation of an item number-reading command, an information-adding command, and an information-subtracting command, a function register coupled to said function setter for storing the command generated by said function setter, an indicator scanner coupled to said code register counter and said I/O register, an indicator unit coupled to said indicator scanner and having a first display station for displaying the item number stored in said code register counter, a second display station for displaying the contents of said I/O register representative of an incoming, outgoing, or current stock quantity, and a control logic circuit responsive to command stored in said function register

for controlling the device, whereby in response to item number-reading command, the entered number is treated as the item number in question and the contents of the memory location identified by that item number displayed; in response to the information-adding command the entered number is treated as the incoming quantity and the contents of the then addressed memory location is incremented by that incoming quantity; and in response to the information-subtracting command, the entered number is treated as the outgoing quantity and the contents of the then addressed memory location is decremented by that outgoing quantity.

3. The inventory control device of claim 2 wherein said function setter includes further a switch for generation of a successive reading command, whereby in response to the successive reading command the item number stored in said code register counter is incremented by one at a time and the contents of the memory location addressed by the incremented item number is displayed.

4. The inventory control device of claim 2 wherein said memory means is a rotary type magnetic storage device.

5. The inventory control device of claim 2 wherein said function setter includes further an erasing command generating switch to initiate the device and an additional switch to inhibit a write operation of said read/write circuit.

6. The inventory control of claim 2 wherein said function setter includes a fourth command generating switch for generation of a successive read command, said control logic circuit operable in response to the successive read command stored in said function register to increase by one the contents of said code register counter and, in response to the coincidence signal from said coincidence circuit, the output of said read/write circuit being coupled to the input of said I/O register.

7. The inventory control device of claim 2 including further a manual switch which when actuated prevents the instruction to effect write operation from said control logic circuit from reaching said read/write circuit.
